(57) **CLAIM**

The ornamental design for a distillation tube with fraction collector, as shown and described.

DESCRIPTION

FIG. 1 shows a top and side perspective view of a distillation tube with fraction collector.

FIG. 2 shows a bottom and reverse side perspective view thereof.

FIG. 3 shows a front elevation view thereof.

FIG. 4 shows a right side elevation view thereof.

FIG. 5 shows a left side elevation view thereof.

FIG. 6 shows a top plan view thereof.

FIG. 7 shows a bottom plan view thereof; and,

FIG. 8 is a cross sectional view taken in the direction of 8-8 in FIG. 5.

The distillation tube with fraction collector is shown with a symbolic break along its length. The appearance of any portion of the article between the break lines forms no part of the claimed design.
